PEBBLE HEATER APPARATUS AND METHOD
FOR HEAT EXCHANGESam P. Robinson, Bartlesville, Okla., assignor to
Phillips Petroleum Company, a corporation of
Delaware

Application January 2, 1948, Serial No. 186

13 Claims. (Cl. 196—55)

1

This invention relates to an improved process for the continuous transfer of heat from a heating zone to a heat absorption zone. In one specific aspect it relates to an improved process for conducting endothermic chemical reactions at high temperatures. In another specific aspect it relates to an improved process for conducting hydrocarbon conversions at elevated temperatures. In still another aspect it relates to an improved pebble heater.

In the pebble heaters of the prior art, various arrangements are employed for recovering the heat from the reaction products and the pebbles after they have passed through the reaction zone, but essentially these heaters comprise a pebble heating zone directly above a reaction zone. Hot combustion gases flow into the lower portion of the heating zone and contact the pebbles just before the pebbles flow through a constricted throat into the reaction zone. In these heaters the pebbles are introduced into the top of the heating zone and are allowed to flow downward through this zone by gravity in direct contact with the upward flowing heating gases. There is no method for producing a completely uniform flow of pebbles through such a heating zone and some pebbles flow through the heating zone considerably faster than others. Since the distribution of the up-flowing heating gases is fairly even throughout the heating zone, those pebbles having the longer residence time in this zone are heated to a much higher temperature than those which pass through rapidly. It is easily possible that the temperatures vary between individual pebbles as much as 500° F.

In a hydrocarbon conversion process, an optimum cracking temperature is selected but in the heaters presently in use, some of the pebbles will be hotter and some colder than this optimum. The hydrocarbons which contact the cool pebbles will be undercracked and the hydrocarbons which contact the hot pebbles will be overcracked. This results in a low yield of desired products, and in addition, the overcracking tends to coke up the pebbles and the gas outlet. Unfortunately, there is no chemical equilibrium between overcracked and undercracked gases to equalize the effect of hot and cold pebbles.

Another undesirable result of uneven heating of pebbles is excessive pebble breakage or spalling from thermal shock. These refractory pebbles, which are used in high temperature systems, are heated to high temperatures and then suddenly cooled. This produces severe internal stresses within the pebble. In an effort to compensate for

2

or counteract these internal stresses, there occurs within the pebble a rapid increase in crystal size. As the crystals increase in size, many small crystals are absorbed by the larger reinforcing crystals with a resulting shattering of many crystal to crystal face bonds and lowered resistance to physical shock. Finally, the pebbles are broken, either from the thermal shock or physical shock in handling, or both.

10 I propose to remedy these faults by providing a pebble tempering or soaking zone between the usual heating zone and the absorption zone. The pebbles flow downward through the heating zone into the tempering zone and thence downward 15 therethrough into the reaction zone. Thus, the pebbles are contacted by the hottest gases immediately on flowing into the tempering zone. The hot combustion or heating gases are introduced into the upper portion of the tempering zone and are caused to flow downward through the tempering chamber concurrently with the pebbles and are removed through a gas outlet in the lower portion of said tempering zone. These gases are moved through a conduit to a 20 gas inlet in the lower portion of said heating zone and are caused to flow upward through said heating zone countercurrently to the pebbles to be removed through a vent in the upper portion of said heating zone. By this concurrent flow, the heating gases and the pebbles approximate a 25 state of thermal equilibrium for a considerable time before the pebbles leave the tempering zone, thereby producing a more uniform temperature throughout the entire fluent mass of pebbles and 30 relieving internal stresses within the pebbles before said pebbles are quenched in the reaction zone.

35 The principal object of my invention is to provide an improved method of transferring heat from a heating zone to an absorption zone.

40 Another object is to provide an improved continuous process for conducting endothermic chemical reactions at high temperatures.

45 Still another object is to provide an improved pebble heater.

50 Numerous other objects and advantages will be apparent to those skilled in the art from reading the following specification, claims, and the accompanying drawings.

In the drawings:

Figure 1 is an elevational view, with parts conventionally shown and parts broken away, of a pebble furnace embodying the present invention.

55 Figure 2 is a modification of 1 showing the

preheating and tempering zones combined in a single chamber.

Figure 3 is a graphic representation of pebble life at various temperatures.

In Figure 1, number 5 is the conversion or heat absorption chamber showing the refractory lining 6, insulating wall 6a, and outer wall 6b, and pebbles 7. The reactant materials flow through conduit 8 into the reaction chamber and upward through the downward moving pebbles, and the reaction products are removed through conduit 9 to an external water quenching zone 10, and from there to a product recovery system (not shown). The flow of pebbles 11 from the reaction chamber through pebble outlet 12 is controlled by a rotary valve 13. These pebbles flow through the pebble conduit 14 into the inlet 15 of a pebble conveyor 16, here shown as a bucket type conveyor. The pebbles are lifted by this conveyor and discharged through outlet 17 into pebble conduit 18 through which they move into pebble heating chamber 19.

As the pebbles flow downward through the heating chamber, they are met by the upward flowing heated gases introduced into a lower portion at gas inlet 20 of said heating chamber through conduit 21. These gases are removed from an upper portion of heating chamber 19 through an exhaust conduit 22. The pebbles flow from the heating chamber through a constricted throat 23 into the tempering chamber 24. Air and a combustible material, such as hydrocarbons, are burned in an external combustion chamber 26 and the hot gases are introduced into the upper portion of the tempering chamber at gas inlet 25 through conduit 27, controlled by a valve 28. If desired, a portion of the hot gases may be introduced directly into the heating chamber 19 at gas inlet 30 through conduit 29 controlled by valve 31. The hot gases flow downward through the tempering chamber concurrently with the moving bed of pebbles and are removed at gas outlet 32.

The tempering chamber and the reaction chamber are in communication with each other by means of a constricted throat 33 similar to the one between the heating and the tempering chambers. To prevent the loss of reaction products by their flowing from the reaction chamber into the tempering chamber and also to prevent the contamination of the reaction products by combustion gases flowing from the tempering chamber into the reaction chamber, a stream of steam is introduced through line 34 into constricted throat 33, thus blocking the flow of gases in both directions.

In Figure 2, heating gases are admitted into the combined heating and tempering chamber 36 through a gas conduit 37 which discharges into the tempering zone 38 of the combination chamber at a point intermediate the middle and the bottom. The downward flowing stream of gases is removed near the bottom of the tempering zone through gas conduit 32, which branches downstream, one stream 39 flowing into the heating zone through variable delivery gas pump or blower 40, the other stream flowing through branch 41, controlled by throttle valve 42 to join the exhaust line 22 of the heating zone 43 at a point downstream of throttle valve 44.

Figure 3 is a graphic representation of the life of a high grade of alumina pebbles at various pebble temperatures. The range of 1700° F. to 2500° F. represents the temperatures to which pebbles are heated in usual pebble furnace operations. These pebbles have a melting point of

about 3700° F. Above 2000° F., they begin to lose rigidity and become subject to plastic deformation when under intense strain. However, these pebbles do not exhibit crystal growth on continuous heating at 3000° F. for 25 hours. It is therefore evident that the breakage of pebbles is not attributable to heating alone, but is the result of internal stresses produced by heating and cooling without any provision for stress relieving.

10 After an examination of these curves, the disadvantages of countercurrent heating of pebbles without any tempering are readily apparent.

Operations

15

My invention is adapted to a wide variety of processes wherein heat must be supplied to an absorption or reaction zone for conducting endothermic chemical reaction at high process temperatures, e. g. above 1000° F. It is particularly adapted to thermal cracking of light hydrocarbons. This heat transfer is accomplished by heating a mass of refractory pebbles in a heating zone and allowing them to flow in a continuous

20 stream through the reaction zone where the pebbles give up part of their sensible heat to the reaction and are then transferred back to the heating zone for recycling through the system.

The pebbles referred to herein preferably are of 30 a refractory material and of such shape that they will flow readily through the chambers or zones. However metal alloys such as high chrome, chrome-nickel or chrome-moly steels may be used at the lower temperature levels. However, for 35 high temperature levels, the pebbles are preferably of a more highly refractory material such as alumina, zirconia, or mullite. They are preferably spherical in form and may range in size from $\frac{1}{8}$ inch to 1 inch, but sizes of $\frac{1}{4}$ inch to $\frac{1}{2}$ inch are preferable.

I make use of three chambers or zones, preferably in substantially vertical arrangement, through which pebbles pass. The lower chamber 5 is a conversion or absorption chamber where the 40 pebbles 7 are contacted with the reactant or absorption materials. Above this conversion chamber and in communication therewith by means of a constricted throat 33 is a chamber 24 which I have chosen to call a tempering chamber, and above the tempering chamber and in communication therewith by means of a constricted throat 23, is a pebble heating chamber 19.

As the pebbles flow from the heating chamber into the tempering chamber, they are contacted 55 by hot gases, usually combustion gases, from an outside source, which gases enter the upper portion of the tempering chamber through conduit 27. These gases are caused to flow downward through the tempering chamber concurrently 60 with the heated pebbles and are removed at or near the bottom of the tempering chamber through an external conduit 21 which leads to the lower portion of the heating chamber 19 above. The gases move upward through the 65 heating chamber countercurrently with the pebbles and are removed through an exhaust vent 22 in the top of the heating chamber.

This function of the pebble heating chamber is 70 the same as that of other pebble heaters where the pebbles are heated by direct contact with a countercurrent stream of hot gases. The length of the constricted throat between the heating and tempering chambers and the location of the gas inlet 25 and outlet 32 in the tempering chamber and the gas inlet 35 in the heating chamber are

75

such that the resistance to the flow of hot gases entering the upper portion of the tempering chamber is lower in the downward direction than in the upward direction, thus causing the gases to flow downward through said tempering chamber.

In a heat transfer system wherein efficient removal of heat from the heating gases is of greater importance than uniformity of pebble temperatures, countercurrent contact between heating gases and pebbles would be advisable. However, if uniformity of pebble temperatures is of greater importance, concurrent contact would be better. I achieve both the uniformity of pebble temperatures and efficient heat removal in my invention. In a countercurrent system, the temperature of the absorbing material is low on entering the heating chamber. The increase in temperature of the pebbles is slow at first and as the pebbles approach the point at which the gases are introduced the temperature increase accelerates rapidly and the rate of increase is greatest at the point where the heating gases are introduced. The spread between the pebble temperature and the heating gas temperature is of a high order of magnitude.

In a concurrent heating system, the temperature rise of the pebbles is extremely rapid when the pebbles and heating gases first establish contact, with the result that during the latter portion of the residence time of the pebbles in the tempering chamber, the gases and pebbles are substantially in thermal equilibrium. The final spread between gas temperature and pebble temperature is very narrow. The result of this is a substantially uniform temperature throughout the fluent mass of pebbles and a substantially uniform temperature throughout the mass of each individual pebble.

It may in some cases, be advantageous to supply only part of the fresh heating gases to the tempering chamber and at the same time admit a part of the heating gases to the preheating zone. By having adjustable controls 28 and 31 on the fresh gas supply to each chamber, a wide range of flexibility is possible for meeting various heating and temperature demands.

The middle tempering chamber 24 is the most important feature of my invention. As related above, the pebbles are contacted by the heated gases immediately on flowing into the tempering chamber and these gases flow through the tempering chamber concurrently with the pebbles. Two important results are achieved by the concurrent flow. In the first place, temperature variations within the fluent mass are equalized so that the temperature throughout approximates the optimum or predetermined temperature. In the second place, internal stresses in the pebbles produced by too rapid heating are relieved by prolonged contact between the pebbles and the hot gases. When the pebbles enter the reaction chamber and their heat is suddenly removed, the strain on the pebbles is not as great as in the usual process where there is no stress-relieving.

In a modification of my invention, the pebble heating and tempering zones may be combined in a single unit 36. In this case, the heating gases are introduced into this combination heating and tempering chamber at an intermediate point and are caused to flow upward and downward from the inlet 30 in countercurrent and concurrent contact with the downward flowing pebbles. The downward flowing gases are removed near the bottom of tempering zone through conduit

32 and all or a part of them are introduced into the pebble heating zone at a point upstream of the heating gas inlet 30 with respect to the flow of pebbles. The combined upward flowing stream of gases is removed near the top of the heating zone through conduit 22. The spent heating gases may be transferred to a heat exchanger for further recovery of the heat.

My invention will be more fully appreciated by reference to the following examples, which have been selected to show, in a minimum of space, the advantages to be gained through my invention.

Example I

15 The following is an example of the effect of uneven pebble temperature in a hydrocarbon cracking system for the production of ethylene. A feed stock of 75 mol per cent of propane and 25 mol per cent of ethane is to be cracked at a temperature of 1600° F. for the production of ethylene. Using reaction velocity constants and product distribution analyses as reported by Schutt in Chemical Engineering Progress, March 1947, pp. 103-116, a reaction time of 0.26 second 20 will allow 95% cracking of the propane and 73% cracking of the ethane. The product gas distribution under these conditions is shown in the first column of Table I.

25 The actual pebble temperatures vary from 1500° F. to 1700° F., a conservative range in the present type pebble heaters, and 25% of the total feed is cracked at 1500° F., 25% at 1700° F., and only 50% at the design temperature of 1600° F. The gases and amounts produced would be as shown 30 in the last four columns of Table I.

TABLE I
Feed stock, 25 mol per cent C_2H_6 + 75 mol per cent C_3H_8 .
Design Temperature, 1600° F.
Reaction Time, 0.26 second
40 Total Feed, 100 mols

	Uniform	Non-uniform			(Composite)
		1,600	1,500	1,600	
Temperature, ° F.	1,600	1,500	1,600	1,700	-----
Degree of C_3H_8 cracking, percent	95	73	95	100	-----
Degree of C_2H_6 cracking, percent	73	35	73	93	-----
Reaction Products:		Mols product gas/100 Mols of Feed			
H_2	45.0	5.9	22.5	12.7	41.1
CH_4	64.3	9.2	32.2	19.9	61.3
$C_2H_4^*$	45.5	9.0	24.2	9.7	42.9
C_2H_6	22.5	6.2	11.3	5.2	22.7
C_3H_6	3.5	3.2	1.7	0.2	5.1
C_3H_8	4.3	5.1	2.1	0.2	7.4
C_4+	3.2	0.2	1.6	1.1	2.9
Total	191.3	-----	-----	183.4	

*Includes C_2H_2 .

55 It will be noted that by employing uniform cracking conditions instead of non-uniform, the ethylene concentration in the product stream is increased from 23.4% to 25.4%, an improvement of 8 1/2%, and the production of ethylene per 100 mols of feed is increased by 13%.

60 This is a single example of the effect of non-uniform heating of pebbles. It is probable that there would be an even greater spread in actual pebble temperatures with present type heaters, and the disadvantages would be even more pronounced.

65 While a process has been described wherein my invention is useful, it is to be understood that its use is not limited to any specific process but is valuable in any pebble heater. My invention is not limited by any specific examples, but is 70 limited only by the following claims.

Having described my invention, I claim:

1. In a continuous process for the transfer of heat from a heating zone to an absorption zone which comprises passing a stream of solid heat transfer elements through a series of zones comprising at least a preheating zone, a tempering zone and an absorption zone, the improvement which comprises passing the elements through said preheating zone in direct contact with a countercurrent stream of hot gases; passing the preheated elements through said tempering zone in the absence of combustion therein and in direct contact with a concurrent stream of hot gases of sufficient temperature and quantity and for a sufficient period of time to temper said elements and approximate a state of thermal equilibrium between hot gases and elements; passing the elements from said tempering zone into and through said absorption zone whereby heat is supplied to said absorption zone; and returning the elements to said preheating zone for recycling.

2. In a continuous process for the transfer of heat from a heating zone to an absorption zone which comprises passing a stream of solid heat transfer elements downward through a series of zones comprising at least a preheating zone, a tempering zone and an absorption zone, the improvement which comprises passing the elements downward through said preheating zone in direct contact with a counter current stream of effluent hot gases from said tempering zone; passing the preheated elements downward through said tempering zone in direct contact with a concurrent stream of hot combustion gases which are hottest at the top of said zone and of sufficient temperature and quantity and for a sufficient period of time to temper said elements and approximate a state of thermal equilibrium between hot gases and elements; passing the elements from said tempering zone downward into and through said absorption zone whereby heat is supplied to said absorption zone; and returning the elements to said preheating zone for recycling.

3. In a continuous process for the transfer of heat from a heating zone to an absorption zone which comprises passing a stream of solid heat transfer elements downward through a series of zones comprising at least a preheating zone, a tempering zone and an absorption zone, the improvement which comprises passing the elements downward through said preheating zone in direct contact with a countercurrent stream of mixed gases composed of the hot effluent gases from the tempering zone and additional fresh hotter gases; passing the preheated elements downward through said tempering zone in direct contact with a concurrent stream of hot combustion gases which are hottest at the top of said zone and of sufficient temperature and quantity and for a sufficient period of time to temper said elements and approximate a state of thermal equilibrium between hot gases and elements; passing the elements from said tempering zone downward into and through said absorption zone whereby heat is supplied to said absorption zone; and returning the elements to said preheating zone for recycling.

4. In a continuous process for the conversion of hydrocarbons at elevated temperatures which comprises passing a stream of solid heat transfer elements downward through a series of chambers comprising at least an element preheating chamber, an element tempering chamber, and a conversion chamber; passing a stream of hot combustion gases through the tempering and preheat-

ing chambers in direct contact with the elements thereby heating them substantially above the predetermined conversion temperature, contacting said elements in the conversion chamber with a stream of hydrocarbons under conditions resulting in the desired conversion and passing the elements from the bottom of the conversion chamber back to the top of the preheating chamber for recycling through the system; the improvement comprising passing the elements first downward through the preheating chamber in direct contact with a countercurrently moving stream of effluent hot gases from the tempering chamber, and then passing the hot elements from the preheating chamber through the tempering chamber in direct contact with a concurrently moving stream of hot combustion gases which are at sufficient initial temperature to heat the elements to the predetermined temperature substantially immediately, and then maintaining the hot elements in contact with the hot combustion gases during the time of stay in the tempering chamber whereby a substantially uniform temperature of the elements entering the conversion chamber is produced.

5. In a continuous process for the conversion of hydrocarbons at a temperature of 1100° F. to 3500° F. which comprises passing a stream of heat transfer pebbles downward through a series of substantially vertically arranged chambers, comprising at least an upper pebble preheating chamber, a middle pebble tempering chamber, and a lower conversion chamber; passing a stream of hot combustion gases through the tempering and preheating zones in direct contact with the pebbles thereby heating them substantially above the predetermined conversion temperature, contacting said pebbles in the conversion zone with a stream of hydrocarbons under conditions resulting in the desired conversion and passing the pebbles from the bottom of the conversion chamber back to the top of the preheating chamber for recycling through the system; the improvement which comprises passing the recycled pebbles first downward through the preheating chamber in direct contact with a countercurrently moving stream of effluent hot gases from the tempering chamber, and then passing the hot pebbles from the preheating chamber through the tempering chamber in direct contact with a concurrently moving stream of hot combustion gases which are at sufficient initial temperature to heat the pebbles to the predetermined temperature substantially immediately, and then maintaining the hot pebbles in contact with the hot combustion gases during the time of stay in the tempering chamber whereby a substantially uniform temperature throughout the mass of recycled elements is produced.

6. In a continuous process for conducting endothermic chemical reactions at elevated temperatures which comprises passing a stream of pebbles downward through a series of substantially vertically arranged chambers, comprising at least an upper pebble preheating chamber, a middle pebble tempering chamber, and a lower reaction chamber; passing a stream of hot combustion gases through said tempering and preheating chambers, whereby the pebbles are heated substantially above the predetermined reaction temperature, contacting said pebbles in the conversion chamber with a stream of reactants under conditions resulting in the desired reaction and passing said pebbles from the bottom of the reaction chamber back to the top of the preheating

chamber for recycling through the system; the improvement which comprises passing the pebbles first downward through the preheating chamber in direct contact with a countercurrently moving stream of effluent hot gases from the tempering chamber, and then passing the hot pebbles from the preheating chamber through the tempering chamber in direct contact with a concurrently moving stream of hot combustion gases which are at sufficient initial temperature to heat said pebbles to the predetermined temperatures substantially immediately, and then maintaining said pebbles in contact with the hot combustion gases during the time of stay in said tempering chamber thereby producing a substantially uniform temperature throughout the mass of said pebbles.

7. In a continuous process for conducting endothermic chemical reactions at elevated temperatures which comprises passing a stream of pebbles downward through a series of substantially vertically arranged chambers, comprising at least an upper pebble preheating chamber, a middle pebble tempering chamber, and a lower reaction chamber; passing a stream of hot combustion gases through said tempering and preheating chambers, whereby the pebbles are heated substantially above the predetermined reaction temperature, contacting said pebbles in the conversion chamber with a stream of reactants under conditions resulting in the desired reaction and passing said pebbles from the bottom of the reaction chamber back to the top of the preheating chamber for recycling through the system; the improvement which comprises passing the pebbles first downward through the preheating chamber in direct contact with a countercurrently moving stream of mixed gases composed of the hot effluent gases from the tempering zone and additional fresh hot gases; and then passing the hot pebbles from the preheating chamber through the tempering chamber in direct contact with a concurrently moving stream of hot combustion gases which are at sufficient initial temperature to heat said pebbles to the predetermined temperature substantially immediately, and then maintaining said pebbles in contact with the hot combustion gases during the time of stay in said tempering chamber thereby producing a substantially uniform temperature throughout the mass of said pebbles.

8. A fluid heater for heating fluids with solid heat transfer pebbles, comprising in combination, a heat absorption zone, a pebble tempering zone above and in communication therewith, a pebble preheating zone above said tempering zone and in communication therewith, a combustion chamber external to said tempering zone, means to supply heating gases from said combustion chamber to an upper portion of said tempering zone and a lower portion of said preheating zone, gas conduit means other than the last-mentioned means connecting a lower portion of said tempering zone with a lower portion of said preheating zone, an exhaust gas conduit connected to an upper portion of said preheating zone, a pebble inlet in an upper portion of said preheating zone, said heat absorption zone having a fluid inlet in a lower portion and a fluid outlet in an upper portion, a pebble outlet in a lower portion of said absorption zone, conveyer means for transferring heat transfer pebbles from pebble outlet in said absorption zone to pebble inlet in said preheating zone.

9. A fluid heater for heating fluids with solid

heat transfer pebbles, comprising in combination a heat absorption chamber, a tempering chamber above and in communication with said absorption chamber, a preheating chamber above said tempering chamber and in communication therewith, a pebble elevator having an inlet below and in communication with a lower portion of said absorption chamber and a discharge above and in communication with the upper portion of said preheating chamber, a combustion chamber having an inlet and an outlet, means to supply fuel and air to the inlet of said combustion chamber, a branched conduit connecting the outlet of said combustion chamber with an upper portion of said tempering chamber and with a lower portion of said preheating chamber, a gas conduit connecting a lower portion of said tempering chamber with a lower portion of said preheating chamber, said absorption chamber having a fluid inlet and a fluid outlet, means to supply fluid to be heated to said fluid inlet and conduit means receiving heated fluid from said fluid outlet, quenching means in said conduit means, and an exhaust conduit connected to an upper portion of said preheating chamber.

10. A fluid heater for heating fluids with solid heat transfer pebbles comprising in combination a conversion chamber, a tempering chamber above and in communication with said conversion chamber, a preheating chamber above and in communication with said tempering chamber, a pebble elevator having an inlet below and in communication with said conversion chamber and a discharge above and in communication with said preheating chamber, a combustion chamber having an inlet and an outlet, means to supply fuel and air to the inlet of said combustion chamber, a conduit connecting the outlet of said combustion chamber with an upper portion of said tempering chamber, a conduit connecting a lower portion of said tempering chamber with a lower portion of said preheating chamber, said conversion chamber having a fluid inlet and a fluid outlet, means to supply fluid to be heated to said fluid inlet and conduit means receiving heated fluid from said fluid outlet, and an exhaust conduit connected to an upper portion of said preheating chamber.

11. A fluid heater for heating fluids with pebbles comprising in combination a conversion chamber, a tempering chamber above and in communication with said conversion chamber, a preheating chamber above and in communication with said tempering chamber, a pebble elevator having an inlet below and in communication with said conversion chamber and a discharge above and in communication with said preheating chamber, a combustion chamber having an inlet and an outlet, means to supply fuel and air to the inlet of said combustion chamber, a conduit connecting the outlet of said combustion chamber with an upper portion of said tempering chamber, a conduit connecting a lower portion of said tempering chamber with a lower portion of said preheating chamber, and an exhaust conduit connected to an upper portion of said preheating chamber.

12. A fluid heater for heating fluids with solid heat transfer pebbles comprising a heat absorption chamber and a single pebble preheating and tempering chamber, said absorption chamber having a fluid inlet below and a fluid outlet above, a pebble outlet in a lower portion and a pebble inlet in an upper portion of said absorption chamber, said preheating and tempering chamber hav-

11

ing a pebble inlet in an upper portion and a pebble outlet in a lower portion, conveyer means for transferring pebbles from the pebble outlet of said absorption chamber to the pebble inlet of said preheating and tempering chamber, pebble conduit means connecting the pebble outlet of said preheating and tempering chamber with the pebble inlet of said absorption chamber, a heating gas inlet in said preheating and tempering chamber in a lower portion of said chamber, means for supplying heating gases thereto, an exhaust gas conduit leading from an upper portion of said preheating and tempering chamber, a branched gas conduit leading from a point of said preheating and tempering chamber lower than said heating gas inlet, one branch of said branched conduit leading to and joining the exhaust gas conduit, the second branch of said branched conduit reentering said preheating and tempering chamber at a point upstream of said heating gas inlet with respect to flow of pebbles and below said exhaust gas conduit, and a blower in said second branch.

13. A fluid heater for heating fluids with pebbles comprising in combination a heat absorption chamber, a pebble tempering chamber thereabove, a pebble preheating chamber above said tempering chamber, pebble throats of much smaller cross-section than said chambers inter-

15

connecting same for downward flow of pebbles therethrough and for preventing substantial flow of gases through said throats from one chamber to another, conveyor means for transferring pebbles from a lower portion of said heat absorption chamber to an upper portion of said preheating chamber, a combustion chamber for generating hot gases, a conduit connecting the outlet of said combustion chamber with an upper portion of said tempering chamber for introducing said hot gases thereto, a conduit connected to a lower portion of said tempering chamber for withdrawing gases therefrom, means to supply heating gases to a lower portion of said preheating chamber, and an exhaust conduit connected to an upper portion of said preheating chamber.
